METHOD AND MEANS FOR DRESSING AND
SHARPENING ROCK DRILLS

Ernest Craig, Falconbridge, Ontario, Canada

Application July 31, 1941, Serial No. 404,783

8 Claims. (Cl. 90—20)

This invention relates to a machine for dressing the external surface of rock drill bits to a definite size, removing all fins and inequalities which may be produced in the forming dies and to effect the sharpening of the cutting edges of the drill.

The principal objects of the invention are to provide a machine which will enable the production of bits of uniform and properly sized diameters in large quantities so that the sizing and sharpening may be accomplished at the minimum expense of time and labour.

A further object is to provide a mechanism which will operate semi-automatically and which may be easily and quickly adjusted to trim bits of different sizes.

The principal feature of the invention consists in the novel construction and arrangement of mechanism whereby high speed milling cutters provided with peripheral and side-cutting faces, are mounted adjacent to means for holding and rotating the bits to be dressed and whereby such rotatable bit-holding members are moved toward and from the side-cutting faces of the milling cutters with a parallel movement for a predetermined and regulated distance.

Other important features will appear in the following description.

In the accompanying drawings Figure 1 is a longitudinal elevation view of a machine constructed in accordance with this invention looking from the rear side and showing the means of driving the rotatable element.

Figure 2 is an enlarged plan view of one end of the machine showing one of the milling cutters in part horizontal section.

Figure 3 is a plan view similar to Figure 2 showing the means for supporting and rotating the drill to be dressed in horizontal mid-section.

Figure 4 is a vertical sectional detail taken on the line 4—4 of Figure 2.

Figure 5 is an elevational detail looking toward the end of the drill-holding and rotating mechanism and showing a portion of the milling cutter.

Figure 6 is an enlarged elevational detail looking toward the face of the milling cutter and showing the toggle members for supporting the drill-holding and rotating device.

Figure 7 is a plan detail showing a portion of the milling cutter in horizontal section and illustrating the manner of dressing the periphery of the drill.

Figure 8 is a plan detail illustrating the manner of sharpening the points of the bit.

In mining and other industries and occupations requiring the use of rock drills it has been found extremely desirable to use drills of the detachable bit type, and it has also been found to be very important in order to accomplish the best results that the drills should be properly sized so that as holes are bored in the rock, successively decreasing sizes of bits may be used. Further, it is found important that in order to accomplish accurate drilling work the drills should be free from external projections or inequalities, such as fins from dies, and it is to meet these necessary and exacting requirements that this machine has been devised.

Referring to the accompanying drawings, the machine comprises a substantially rectangular-shape frame 1 provided with extension tables 2 and 3 at the opposite ends.

Suitable journals 4, preferably of the ball or roller bearing high speed type, are mounted on top of the frame 1 and support a shaft 5 and upon the ends of this shaft are mounted specially formed milling cutters 6. Each of these cutters is provided with an inverted V-shaped perimeter 11 having cutting teeth formed therein, the angularity of the face of the cutter being the desired angle of bevel of the edges of the drill so that when the end of a drill bit is placed thereagainst the cutter will cut the bit surfaces at the required angle and sharpening of the bit may thus be very quickly effected by pressing same preferably in heated form thereagainst.

Figure 8 illustrates the manner of sharpening the ends of the bit, the bit 8 being shown held by tongs 9 in engagement with the double bevelled surface of the milling cutter 6. The shaft 5 is driven by suitable belts 9' operated by a motor 10 mounted on a platform 11 in the frame 1.

Rigidly mounted on each of the tables 2 and 3 are a pair of vertical posts 12 which are spaced apart, and a line extending through the axes of these posts is arranged parallel to the central vertical plane of the milling cutter.

Mounted upon each of the posts 12, and preferably on ball bearings, is a link member 13 which is formed with a pair of horizontally disposed spaced-apart lugs 14 forming a jaw. This jaw is provided with bushings 15, and mounted in the bushings are flanged studs 16, the inward ends of which are threaded into a block 17. The blocks 17 are bored horizontally and a tube 18 extends through these horizontal orifices connecting the two blocks in alignment.

Bushings 19 are arranged at the opposite ends

of the tube 18 and a shaft 20 is journalled in these bushings. A pulley 21 is mounted on the outward end of the shaft 20 beyond the edge of the table 2 or 3, and this pulley is driven by a belt 22 which extends downwardly around a double pulley 23.

These structures are preferably duplicated at each end of the machine and one of the double pulleys is driven from a shaft 24 of a gear reduction device 25 mounted on the frame 1. The other double pulley is mounted on a suitable bracket support 26 at the other end of the machine and a crossed belt 27 extends between these two pulleys. The gear reduction mechanism is driven by a suitable motor 28 mounted on the platform 11 of the frame.

On the opposite end of each of the shafts 20 is mounted a spur gear 29. A casing 30, somewhat elliptical in form as shown particularly in Figure 5, is formed in two sections and it is securely bolted in an oblique angular position on the adjacent block 17 carried by one of the links 13.

Within this casing 30 and offset from the shaft 20 is arranged a ball bearing 31 in which is mounted a spindle 32. The cap plate 33 of the casing 30 supports a bushing 34 which supports the spindle in a horizontal position parallel with the shaft 20 and a spur gear 35 is mounted on the spindle and meshes with the gear 29 and is rotated thereby. The outer end of the spindle is provided with a central tapered member 36 and on either side thereof are arranged lugs 37 with V-shaped recesses which are adapted to receive the bevel edges of a drill when the drill is inserted over the tapered spur 36.

The milling cutter 6 is formed with side cutting faces 38 which are shaped to engage and cut the outer peripheral surface of the drill bit when such is brought into contact therewith, and the drill bit being mounted on the spindle 32 with its points engaging the V-shaped lugs thereon, being rotated, has its entire perimeter brought into contact with the shaped cutting surface of the milling cutter so that all fins or other inequalities on the surface will be removed and, because of the limitations of movement of the means for supporting the bits hereinafter described, the perimeter of the bit will be cut as it is rotated by the rapidly revolving milling cutter to a desired size.

It has been stated that the shaft 20 is mounted within a tube 18 carried in blocks 17 pivotally mounted in the jaw ends of the link members 13. Consequently when the link members are swung on their pivots the drill-carrying spindle will be moved inwardly with a movement parallel to the vertical plane of the milling cutter.

A cap screw 39 is secured in the top of one of the studs 16 supporting the block adjacent to the drill-holding spindle, and a rod 40 provided with an eye-end 41 rotatably connected with the cap screw, extends angularly outward through a post support 42, which is rigidly secured to the tables. The rod 40 is threaded and on this threaded portion are mounted threaded nuts 43 and 44. The inward nut 43 engaging the post 42 forms a limit to the outward swing of the toggle-supported drill-rotating holder, and the nut 44 is adjusted to limit the inward swing, so that the diameter of the drill, when brought into contact with the milling cutter, may be accurately regulated.

A coiled tension spring 45 is secured at one end to the top of the post 12 adjacent to the drill-holding spindle. The other end is secured to

the top of the stud 16 of the opposite toggle. The pull on this spring holds the tube 20 and its toggle and the drill-holding spindle in the outward position.

5 In order to dress the periphery of a drill bit it is merely necessary to place the drill on to the end of the tapered extension 36 of the rotatable drill holder, and upon pressing it home so that the points enter the notches in the lugs 37, and applying a further pressure the entire rotating mechanism supported on the swinging toggles, will swing toward the milling cutter as indicated by the broken lines in Figure 2, and the periphery of the drill bit will be brought into engagement with the toothed side face 38 of the milling cutter, as is illustrated in Figure 7.

The adjustment of the nut 44 on the outer end of the rod 40 limits this inward movement so that the drill bit can only move a predetermined 10 distance inwardly in engagement with the rotating milling cutter and upon release of the inward pressure by the operator upon the drill, the spring 45 swings the drill-holding member outwardly, ready for the next bit.

15 The variations in sizes of bits requires considerable flexibility of adjustment. Consequently the tables supporting the drill-holding members is preferably provided with a movable plate 46 which may be adjusted by means of the cranked 20 screw 47. A suitable locking screw 48 extending through a slot 49 in the plate secures the plate firmly in the desired position.

25 I have shown and described the machine as a double machine, that is to say, the main shaft 35 has milling cutters mounted on both ends and the drill-holding mechanism is duplicated at each end of the machine, but it will be readily understood that a single machine may be provided, but the dual machine operates to double 30 capacity with a single main drive shaft motor and a single drill feed operating motor through the arrangement described.

35 It will be appreciated that many variations in the detail construction of this machine may be 40 made without departing from the principal features which are to provide a cutter for sharpening and cutting the perimeter of the drill and means to support and rotate the drill which will move toward and from the cutter with a parallel 45 movement, to accurately size the same, and either one of both of these operations may be carried out while the bit is in heated or heat-softened condition, the sizing operation being 50 preferably carried out immediately following the sharpening or dressing operation or vice versa.

55 What I claim as my invention is:

1. A means for dressing rock drills, comprising a rotatable cutter, power driven rotatable means for supporting the drills having its axis 60 parallel to the axis of the cutter, pivotal means for supporting said rotatable drill-supporting means movable toward and from said cutter upon the application of endwise pressure upon the bit with a movement parallel to the axis of 65 said cutter to bring the perimeter of the drill into engagement with the side face of the cutter, and adjustable means for limiting the movement of the drill-supporting member toward the cutter.

70 2. Means for dressing rock drills, comprising a rotatable cutter having a cutting side face shaped to trim the drill, a power driven rotatable spindle parallel with the axis of said cutter for holding the drill and rotating same in contact 75 with the cutter, means supporting said rotatable

drill-holding spindle pivotally mounted to move said spindle with a movement parallel to the cutter axis toward and from the cutter upon the application of endwise pressure upon the bit, and adjustable means for limiting the inward swinging movement of the drill-holding member to size the drill in engagement with the cutter.

3. A means for dressing rock drills, comprising a rotatable cutter having an end face shaped to dress the perimeter of a drill when brought in contact therewith, a pair of pivotal links mounted on rigid pivots at one end, a shaft supported between the free ends of said links, a spindle journaled parallel with said shaft and geared thereto and movable therewith on the pivotal links, said spindle being adapted to receive and hold the drill and upon the swinging of the links to move the drill into contact with the cutter, means for limiting the inward movement of said links and the drill-supporting spindle, and means for moving the spindle and its operating shaft outwardly away from the cutter.

4. A machine for dressing rock drills, comprising a frame, a shaft journaled horizontally on said frame, a milling cutter mounted on said shaft and having a cutting end face shaped to trim the perimeter of a drill, a table extension from said frame, a pair of posts mounted on said table extension, a pair of link members pivotally mounted on said posts, blocks pivotally mounted on the free ends of said links, a shaft rotatably supported from said blocks, a spindle geared to the latter shaft and having drill point engaging lugs, means for limiting the swinging movement of said links and the movement of said shaft and spindle toward said cutter, means mounted in the frame for rotating the cutter shaft, and means mounted in the frame operatively connected to rotate the drill-supporting spindle shaft.

5. A machine for dressing rock drills, comprising a frame, a cutter shaft horizontally mounted on the frame, a milling cutter mounted on said cutter shaft having a cutting end face, a pair of links pivotally supported from said

frame, a rotatable spindle pivotally supported from said links adapted to rotatably support a drill, said links being adapted to effect the movement of the drill into peripheral contact with the end cutting face of the milling cutter, a threaded bar pivotally connected to the swinging end of one of said link supports, a post rigidly mounted on said frame having an eye end through which said threaded rod extends, and adjusting nuts threaded on said rod either side of said post to limit the swinging movement of said links and the drill-holding spindle.

6. A device as claimed in claim 3 having a tension spring connected to the free end of one of said links and exerting a pull against the swinging of the links and the bit-supporting spindle toward the cutter.

7. A machine for dressing rock drills, comprising a frame, a cutter shaft horizontally mounted on the frame, a milling cutter mounted on said cutter shaft, a shaft in right angular relation to said cutter shaft and arranged adjacent to the cutter, a drill-holding member driven from said latter shaft, means for movably supporting said latter shaft and spindle to bring the drill into engagement with the cutter, a motor on said frame operatively connected to rotate said latter shaft, and a motor on said frame operatively connected to drive said cutter shaft.

8. A machine for dressing rock drills, comprising a frame, a cutter shaft horizontally mounted on the frame, a milling cutter mounted on said cutter shaft, a shaft in right angular relation to said cutter shaft and arranged adjacent to the cutter, a drill-holding member driven from said latter shaft, means for movably supporting said latter shaft and spindle to bring the drill into engagement with the cutter, a motor on said frame, a flexible operating connection between said motor and said latter shaft to rotate same constantly during the movement of the shaft-supporting means, and a motor operatively connected to drive the cutter shaft.

ERNEST CRAIG.
